UNITED STATES PATENT OFFICE.

HERBERT BERKLEY BRYANT, OF MANCHESTER, NEW HAMPSHIRE.

CURRIER'S KNIFE.

SPECIFICATION forming part of Letters Patent No. 444,724, dated January 13, 1891.

Application filed September 13, 1890. Serial No. 364,905. (No model.)

To all whom it may concern:

Be it known that I, HERBERT BERKLEY BRYANT, of Manchester, in the county of Hillsborough, in the State of New Hampshire, a citizen of the United States, have invented a new and useful Improvement in Curriers' Knives, of which the following is a specification, reference being had to the accompanying drawings, forming a part thereof, in sufficiently full, complete, and accurate terms to enable a person skilled in the art to make and use my invention.

In the drawings, Figure 1 is a side elevation of a currier's knife of my improved construction. Figs. 2 and 3 form a broken longitudinal section of the same on the line $z z$ of Fig. 1 on a larger scale, Fig. 2 of which is divided into two parts in the center of the handle T in order to make the drawing more compact endwise, and Fig. 2 is separated from Fig. 3 by a break which would represent the central portion of the knife shown in Fig. 1. Fig. 4 is a transverse section of the knife upon the line $y y$ of Fig. 1. Fig. 5 is a transverse section upon the line $x x$ of Fig. 1. Fig. 6 is an elevation of the cross-handle, taken from the knife side of the handle; and Fig. 7 illustrates a section of the ordinary currier's knife now in use at a point which corresponds to the section-line $x x$ of Fig. 1.

Curriers' knives as now made are composed of six general elements or parts. These elements are the cross-handle at one end, the longitudinal handle at the other end, the straps which extend from one handle to the other and are provided with tangs or extensions which enter the handles and fasten the straps to the handles, and the two blades which are nipped between the straps and which serve to do the work. The transverse section in these straps in the knives as at present constructed is like the transverse section shown in Fig. 7. Here it will be seen that each strap is shaped something like an isosceles triangle with a comparatively long base and small altitude and with the apex truncated or flattened sufficiently to allow room for the binding-screws. The straps are symmetrical, and they are marked in the drawing Fig. 7, $A a A' a$, and the flattened surface is marked $p b$ and the inclined outer surfaces are marked $p a$. The blades are

marked B . The screw which unites the straps together and nips the blades between them is marked $c a$. It will be noticed that this screw is perpendicular to the flat surface $p b$ and perpendicular to the plane of the blades. I have changed the shape of the transverse section of these straps and the position of the binding-screw therein. The reason for changing the shape of the strap is this: It is necessary to grind the edges of the blades B with a long bevel on one side and a short bevel on the other in order that a wire edge may be formed upon the edge of the scrapers to more readily take hold of the work. As however, it is necessary to grind these edges of the blades B from time to time, it has been found that the strap is apt to be ground with the edge of the blade on the side on which the long bevel is made, also when by use the blades have become narrow in the old style of knife it is impossible to grind a thin edge on them, and they become useless, and that this injures the strap, and in case the head of the screw which unites the strap together is not a countersunk head injures the screw-head. I have therefore made the transverse section of the straps at the place where they engage the blade in the form of a scalene triangle, of which one side corresponds to one of the sides $p a$ of Fig. 7 and the other side corresponds with a line drawn from the upper termination of the line $p a$ to the outer termination of the next adjacent side $p a$ beyond the flattened surface $p b$, and therefore have obliterated one of the apices or arêtes which lies between the flattened surface $p b$ and the inclined surface $p a$. This is shown very clearly in Figs. 4 and 5, which represent the transverse sections taken on the lines $x x$ and $y y$ of Fig. 1. In this way the two straps A and A' of Figs. 4 and 5 present two opposite parallel surfaces s , which are of about two-thirds of the width of the strap, and two opposite parallel surfaces p , which are of about one-third of the width of the strap measured horizontally or on the line of the plane of the blades. In constructing the straps of this transverse section the position of the screw which fastens them together is somewhat altered. A reference to Fig. 5 shows that the screw c , uniting the straps, binds them together on a line perpendicular

to the faces *s*, which line is inclined to the line of the screw in the old-fashioned currier's knife, (shown in Fig. 7,) as the axis of the screw *c* of Fig. 5 is inclined to the dotted line *w* in that figure. It will be obvious that this change allows the long bevel of the blades *B* to be ground without danger of touching the straps to the stone much more readily than with the old form. In addition to this, in the old form of knives the tangs at either end of the straps which fastened them to the handles had an internal angle at their junction with the body of the straps, as shown in the illustration of curriers' knives found on page 424 of *Davis's Manufacture of Leather*, published by Henry Carey Baird & Co., Philadelphia, 1885, and the sectional form of the tang of the straps was usually, if not always, square. Besides this, it was customary to have the ends of the blades extend a little beyond the ends of the broad portions of the strap, so that the blade made a narrow and comparatively sharp bearing for the fingers of the operator. My improvement in this part of the knife is to have the straps long enough to cover the edges of the blades and to curve them into the tang gradually, so as to form a smooth seat for the fingers of the operator, so that the operator's hand shall be in no danger of callus or injury. This is shown clearly in Fig. 1. The straps at their cross-handle end are formed into tapering tangs, as shown in Fig. 3, which terminate in screw-threads on their exterior at the outer end. These tangs are made, as shown in Fig. 6, at the point where they enter the handle square, thus having a partial shoulder toward the blades. These tapering tangs are lettered *f* in Figs. 3 and 6. The cross-handle is lettered *O*. A tapering bore is made in it to conform to the shape of the tang, and at the outer end of this bore a recess is made for the insertion of the nut *g*, which is driven upon the tangs by a spanner in the usual way. On the inner side of the cross-handle *O* another recess is made for the insertion of the bushing *V*, which bushing has, as shown in Fig. 6, a square hole in its center for the reception of the tangs, and is held in place on the handle by means of two screws *r*, which are driven into the handle and engage with notches on the exterior of the bushing *V*, and thus prevent it from rotating, and also prevent the cross-handle *O* from turning upon the tang. Of course the bushing *V* may be held in its place in any other suitable and well-known manner. The employment of screws engaging with notches is a simple contrivance, and one which any ordinary mechanic could well execute. The long tang at the opposite end of the straps from the cross-handle is marked in the drawings *d*. It is usually made rounding, and between it and the strap proper is a shoulder, (marked *h* in Fig. 2.) The straight handle *T* has a metallic ferrule *N* upon its end adjacent to the strap, and this ferrule is so formed that its outer surface shall grad-

ually form a smooth and rounded hollow for the fingers of the operator to clasp if he so desire, and the strap between the ferrule end and the blades is also rounded and smoothed and has a hollow bearing on the side next the blade, so that the fingers shall not be injured upon that side. The outer ends of the tangs *d* have a screw-thread cut upon them, and the nut *e* draws them tightly in and holds them firm. This nut is countersunk into the end of the handle *T* and is set up with a spanner. In order to hold these straps together and nip them upon the blades, I do not depend entirely upon the bind to be got by the more or less tapering form of the tangs where they enter the handle, but I draw the straps together, as shown by screws *c*. Only two of these screws are represented in the drawings; but it is obvious that several may be employed, if desired. Five or six is not an unusual number to be used in the curriers' knives at present in use; but I do not prescribe any particular number, as the number to be employed will depend very much upon the stiffness of the metal of which the straps are composed. In order to more readily loosen the hold of the straps upon the knives, set-screws *a* are driven into the blades adjacent to the screws *c*, and these set-screws may either be driven into a recess in the strap *A'*, as shown in Fig. 4, or might be pointed and engage directly with the surface of the strap *A'*. It is obvious that these two methods would be practically equivalent. I prefer, however, as the surest the making of a small recess, as shown in Fig. 4, for the reception of the end of the set-screw *a*. The smooth rounding hollow between the blades *B* and the cross-handle *O* above referred to is marked *k*, and the smooth rounding hollow between the handle *T* and the blades *B* is marked *l* in Fig. 1. These hollows are illustrated as far as they can be in Figs. 2 and 3 as designated by the same letters.

I claim as my invention and desire to secure by Letters Patent—

1. In curriers' knives, the combination of the blades *B* and straps *A A'*, each having one exterior long surface *s* adjacent to one of the blades and one exterior short surface *p* adjacent to the other of the blades, and each blade having adjacent to it the exterior long surface *s* of one strap and the exterior short surface *p* of the other strap, with suitable means for clamping said straps sidewise on the blades, substantially as and for the purpose described.

2. In curriers' knives, the combination of the two straps *A A'*, each formed with one exterior long surface *s* and one exterior short surface *p*, with the blades *B*, compressed between them, and with the screw *c*, uniting the straps and compressing them upon the blades perpendicularly to the long surfaces *s* of the straps and at an inclination with the blades, substantially as described.

3. In curriers' knives, the combination of the straps *A A'*, each having one exterior long

surface *s* and one exterior short surface *p*, with each other, and with the blades *B*, and with the assembling-screws *c*, and with the set-screws *a*, substantially as and for the purpose described.

5 4. In curriers' knives, the combination of the blades *B* and straps *A A'*, each provided with tangs, with the handle *T* and ferrule *N*, formed with a concave holding-surface presented toward the edge of the blades *B*, substantially as and for the purposes described.

10 5. In curriers' knives, the combination of the blades *B* and straps *A A'*, each provided with a tang *f*, with the handle *O*, having a

bushing *V* recessed into the center of one 15 side of said handle and fixed thereto, substantially as and for the purposes described.

6. In curriers' knives, the straps *A A'*, formed at their ends with the hollow curvatures *h h* and with tangs rounded between the 20 position of the blades and the handles, in combination with the blades *B* and covering the lateral edges of the blades, substantially as and for the purposes described.
